UNITED STATES PATENT OFFICE.

FREDERICK M. FURBER, OF BEACHMONT, MASSACHUSETTS.

PRIMING-CUP.

1,103,137.

Specification of Letters Patent. Patented July 14, 1914.

Application filed February 21, 1912. Serial No. 679,120.

To all whom it may concern:

Be it known that I, FREDERICK M. FURBER, a citizen of the United States, residing at Beachmont, in the county of Suffolk and State of Massachusetts, have invented certain Improvements in Priming-Cups, of which the following description, in connection with the accompanying drawings, is a specification, like reference characters on the drawings indicating like parts in the several figures.

In using a multi-cylinder engine of the internal combustion type it frequently happens that one or more of the cylinders stops firing or refuses to fire upon starting up the engine. It is desirable of course to locate the cylinder that is not working so that the trouble can be determined and remedied, but such engines usually are not equipped with means by which the operator can determine readily which cylinder is idle. The present invention aims to provide means by which this fact can be easily determined. The invention also is directed to the provision of a priming cup of novel construction. Preferably these two features are combined in a single device.

A convenient embodiment of the invention will now be described, reference being made to the accompanying drawings, in which—

Figure 1 is a perspective view of a device embodying the invention; Fig. 2 is a central longitudinal section of the device shown in Fig. 1, but showing the lower portion of the device in side elevation; and Fig. 3 is a sectional view of the body of the device at right angles to the view shown in Fig. 2, certain of the parts being shown in elevation.

The body 2 of the device preferably is made from square bar stock and is turned at its lower end and threaded to form a stem 4 designed to be threaded into a suitable aperture in an engine cylinder. A large hole 6 is drilled in the upper end of the body and a smaller hole 8 is drilled through the body longitudinally thereof from the bottom of hole 6 to the lower end of the stem. The body also is drilled transversely to receive a valve plug 10 having a handle 12 which may be formed from the same stock as the body 2. This handle is drilled as indicated at 14 to form a cup for the reception of priming liquid. The valve plug 10 has a diagonal duct 16 formed therein which connects with a short duct 18 opening into

the bottom of the priming cup 14. It will be evident that when the handle is in the position in which it is shown in Figs. 1 and 2 the duct 16 will be in communication with the passage 8, but that when the handle is turned into the position indicated in Fig. 3 the communication between the cup and the passage 8 will be cut off. The valve plug is held in operative position in the body 2 by a spring 20 and a cotter pin 22.

The valve plug 10 is drilled as indicated at 24 to form an aperture which will register with the passage 8 both above and below the plug when the handle is turned into the position indicated in Fig. 3. The upper part of the passage 8 and the apertures 6 and 24 constitute a sight opening through which an observer may look into the engine cylinder when the valve is in proper position. This opening is closed to prevent the passage of gases therethrough by a bull's-eye 26 of glass or other translucent material which preferably completely fills the hole 24 so that any soot or deposit that collects upon the exposed surface of the bull's-eye will be scraped off when the valve is turned in the body.

It will be evident that when one of these devices is properly attached to each cylinder of an engine the engine may be primed by turning the handle 12 of one or more of these devices into an upright position for pouring the gasoline or other priming fluid into the cup 14. The member 12 thus serves not only as a handle but also as a priming cup. After the priming operation the handle is then turned into a horizontal position thus moving the bull's-eye into alignment with the duct 8 and closing the passage through the duct 16. If it is then found that one of the cylinders is running idle the operator can at once determine which cylinder is not working by looking into the opening 6 of each device. Obviously if the cylinder is firing properly he will see a flash at each explosion. The extension of the body above the bull's-eye 26 provides a comparatively dark space around the bull's-eye, thus enabling the flash to be seen more distinctly.

Having fully described my invention, what I claim as new and desire to secure by Letters Patent of the United States is:

1. A device of the character described, comprising a body constructed to be attached to an engine cylinder and having a

- passage formed therethrough to communicate with the interior of the cylinder, a valve positioned in said body, a bull's-eye carried by said valve and arranged to be moved into and out of alinement with said passage, and a handle for said valve recessed to form a priming cup, said valve being constructed to control the communication between said passage and said cup.
- 10 2. A device of the character described comprising a body constructed to be attached to an engine cylinder and having a passage formed therethrough to communicate with the interior of the cylinder, a priming cup,

a valve arranged to control communication 15 between said priming cup and said passage, and a bull's-eye carried by said valve and arranged to prevent the escape of gases through said passage while affording a view therethrough.

20

In testimony whereof I have signed my name to this specification in the presence of two subscribing witnesses.

FREDERICK M. FURBER.
